PIE CUTTER OR THE LIKE

Gregory E. Palmer, P.O. Box 5002, Detroit, Mich. 48200

Filed June 21, 1965, Ser. No. 85,835

Term of patent 14 years

(Cl. D44—29)

FIG. 1 is a perspective view of a pie cutter or the like embodying my new design;

FIG. 2 is a top plan view of the same;

FIG. 3 is a sectional view of the same, taken along line 3—3 of FIG. 1.

The characteristic feature of the design resides in the contour of the blades, as shown in FIG. 3 of the drawings.

I claim:

The ornamental design for a pie cutter or the like, substantially as shown and described.
